2,560,473

MECHANISM FOR SUCCESSIVELY PRODUCING BAG LENGTHS FROM CONTINUOUSLY ADVANCING TUBULAR WEBS

Adolph Potdevin, Garden City, and Rudolph Paul Bechle, Yonkers, N. Y., assignors to Potdevin Machine Company, Brooklyn, N. Y., a corporation of New York

Application August 18, 1948, Serial No. 44,858

8 Claims. (Cl. 164—68)

1

This invention relates to web cutting apparatus with particular reference to apparatus for properly shaping the end of a tubular web and severing the web into bag lengths.

In manufacturing paper bags, the web from which the bags are fabricated is folded into tubular form and in accordance with the present invention, the tubular web is fed into the machine, its leading end shaped and the web severed to the rear of the leading end to form a bag length, these operations taking place successively, thereby to produce bag lengths continuously.

The present invention will be described in connection with the manufacture of bag lengths for bags of the valve type. This is a well known type of bag and inherently comprises a bag length one end of which is shaped to provide a projection or lip at one corner which later is folded in to form the valve.

One object of the present invention is to provide an apparatus for the general purpose above referred to wherein the cutters for forming or shaping the leading end of the web and the cutter for severing the web back of the leading end into bag lengths move at a proper cutting speed ratio with web speed at the instant of their operation, simple means being provided for adjusting the machine to vary the length of the bag lengths produced thereon, while maintaining the proper relation between the speed of the shaping mechanism and severing mechanism and web speed.

Other objects will appear hereinafter.

In the accompanying drawings:

Fig. 1 is a side elevational view of one embodiment of the invention.

Fig. 2 is a plan view of part of the apparatus illustrated in Fig. 1;

Fig. 3 is a side elevation with some parts broken away, of the apparatus of Fig. 2.

Fig. 4 is a view similar to Fig. 2 of another embodiment of the invention;

Fig. 5 is a side elevation of Fig. 4; and

Figs. 6, 7 and 8 are isometric views of the various steps taken in the manufacture of a bag length from a tubular web.

Referring to the drawings in detail, and, first of all, to Figs. 1, 2, 3 and 6, 7, and 8 of the drawings:

As above explained, the present invention is directed to an improved apparatus for producing bag lengths wherein the bag lengths are cut from a tubular web, one end of the bag length being of a particular shape. For the purpose of illustration and description, valve bag lengths have been shown on the drawings and will be

2

specifically referred to in the specification. It is to be understood, however, that the invention comprehends the production of bag lengths other than those employed in making valve bags. In its broadest aspect the invention is directed to mechanism for the production of bag lengths wherein one end of each length is of some particular shape but not necessarily the shape required when making conventional valve bags.

10 It will be appreciated that in conventional bag forming machines, means are provided for continuously advancing one or more webs of paper from a supply roll or rolls about folding or tubing mechanism, from whence the tubed web passes 15 to the mechanism constituting the subject matter of the instant invention. Inasmuch as the construction of this tubing mechanism forms no part of the present invention, and inasmuch as the same is well known in the industry, illustration and description of the same are unnecessary to a clear understanding of the invention.

As the web, which has been designated W, continuously passes from the tubing mechanism, it passes to feed rollers 2 and feed rollers 4, from 25 whence, in the case of cement valve bags, it passes through perforating mechanism comprising segmental roller 6 and cooperating cylinder 8. The roller 6 is equipped with peripheral pins 10 while the cylinder 8 is equipped with corresponding depressions 12.

30 On continued advance of the web, its leading end is appropriately shaped by suitable mechanism, the web thereafter being severed a bag length to the rear of its leading end and the bag lengths discharged successively from the machine by a pair of discharge rollers.

The web-severing mechanism comprises an upper, positively driven rotor 14, mounted on shaft 16 and carrying severing knife 18 extending 40 transversely of the machine, the knife being of a length sufficient completely to sever the widest web capable of being handled by the machine. Cooperating with the rotor 14 is lower rotor 20, mounted on shaft 22 and provided in its periphery with notch 24 which cooperates with the knife 18 as will be understood.

45 The web-shaping mechanism comprises an upper positively driven rotor 26 mounted on shaft 28 and carrying a blade 30 which extends 50 transversely of the machine and hence transversely of a web passing through the machine. The blade 30, as distinguished from the web-severing knife 18 extends across the web for a portion only of the width of the web. This same rotor 26, adjacent the end of blade 30 carries

a short blade 32 extending circumferentially of the rotor and hence lengthwise of the web.

This web-shaping mechanism comprises also a lower rotor 34 mounted on shaft 36 and provided with appropriate recesses for cooperation with the blades 30 and 32.

From the brief and more or less general description thus far given, it will be appreciated that the short, circumferentially extending knife 32 when it engages the web makes a short longitudinal slit in the web along 40, Figs. 7 and 8. The transverse knife 30 then makes a transverse cut along 38, Figs. 7 and 8, completely to sever the piece 42.

The discharge rollers above referred to and which are designated 44 and 46 are geared together through gears 48 and driven by belt 50 from a variable speed drive such as a Reeves drive indicated at 52.

The web-shaping mechanism and the web-severing mechanism are driven from a main driving motor 54.

The shafts 16 and 28 carrying the web-severing rotor 14 and web-shaping rotor 26, respectively, are equipped with gears 56 and 58, in constant mesh with gears 60 and 62. These gear trains are at the front side of the machine as viewed in Fig. 3.

Mounted in bearings in the side frames 64 and 66 of the machine are transversely extending shafts 68 and 70, these shafts projecting through the machine side frames and at their rear ends as viewed in Fig. 3 carrying gears 72 and 74 respectively, in constant mesh with intermediate gear 76, driven through belt 78, from the main driving motor 54.

At the front side of the machine, as viewed in Fig. 3, we provide two housings 80 and 82 rotatably adjustable on the shafts 68 and 70 respectively. They are held in adjusted position by bolts 84 and 86 screwed into the side frame 64.

Mounted on the inside of the housing 80 is a gear 88 on stub shaft 90, this gear being in constant mesh with gear 92 affixed to the shaft 68.

Affixed to the shaft 22 for the lower rotor 20 of the web-severing mechanism is a bifurcated crank arm 94 and cooperating with this crank arm is a crank pin 96 carried by the gear 88. Obviously by rotatably adjusting the housing 80 on the shaft 68 it is possible to adjust the eccentricity of the circular path of crank pin 96 with the path of crank arm 94, thereby imparting an adjustable pulsating motion to rotor 20.

Mounted on the inside of the housing 82 is a gear 98 on stub shaft 100, this gear constantly meshing with gear 102 affixed to the shaft 70.

Secured to the shaft 36 for the lower rotor 34 of the web-shaping mechanism is a bifurcated crank arm 104, and cooperating with this crank arm is a crank pin 106. Obviously, by rotatably adjusting the housing 82 on the shaft 70 the throw of the crank arm 104 may be varied with relation to the position of rotors 26 and 34.

In the initial starting of the machine it will be appreciated that as the web W is advanced by the feed rollers 2 and 4 it comes up to the web-severing rotors 14 and 20 and is squared off across the end as illustrated at 124 in Fig. 6, the web advancing thereafter until its leading end is engaged by the web-shaping rotors 26 and 34 where a cut 40 is made at the leading end of the web, Fig. 7, followed immediately by transverse cut along 38 completely to sever strip 42 from the web.

As the web advances and after it enters be-

tween the overspeeded discharge rollers 44 and 46 the web-severing rotors 14 and 20 will have been rotated into severing position to sever the web a bag length to the rear of the leading end as seen in Fig. 8.

After the first bag length is cut off, the web is first shaped at its leading end, engaged by the discharge rollers 44 and 46 and then completely severed into bag lengths. Operation is continuous.

It is to be understood that in setting the machine originally for a desired length of bag, the housing 82 is so set that at the instant the web-shaping cutters engage the paper, these cutters will be moving at a desired cutting speed relative to paper speed; it is to be understood also that the housing 80 is so set that at the instant the web-severing knife engages the paper the knife will be traveling at a desired speed relative to paper speed. This adjustment and setting is possible by reason of the adjustability of the crank pins in their respective bifurcated crank arms, shifting these pins along the arms altering the speed at which the rotors will be traveling when the rotors of each pair come to operative position.

When it is desired to make a run of bag lengths either shorter or longer than the machine was originally set for, then it is merely necessary to make a change in the change gear train 112, 114 and 116 to decrease or increase the web speed, depending upon whether shorter or longer bags are to be run. The housings 80 and 82 are then adjusted to vary the relation of the crank pins to their respective cranks, whereby at the new web speed the web-shaping mechanism and the web-severing mechanism will be moving at the desired cutting speed relative to web speed when they contact the web, despite the fact that the speed of motor 54 is constant.

In other words while the rotors 26, 34 and 14, 20 are always driven at a constant number of revolutions per minute, their linear speed is not constant, and by shifting the crank pins in their respective crank arms the peripheral speed at which the rotors are traveling at the instant the two rotors of a pair are rotated into cooperative position may be varied.

Referring to the mechanism illustrated in Figs. 4 and 5, constituting another embodiment of the invention:

In this embodiment of the invention, web-severing rotors 126 and 128 and web-shaping rotors 130 and 132 are provided corresponding to similar rotors described in connection with Fig. 1. 134 and 136 designate the discharge rollers corresponding to discharge rollers 44 and 46 of Fig. 1.

The web-severing rotors are geared together one-to-one through gears 138 and 140 and the web-shaping rotors are geared together one-to-one through gears 142 and 144.

The web-severing and the web-shaping rollers are driven from motor 146, belt 148, intermediate gear 150 and gears 152 and 154, the two latter gears being mounted on shafts 156 and 158 extending transversely of the machine and mounted in bearings in the machine side frames 160 and 162.

The shaft 164 for the lower rotor 128 of the web-severing mechanism projects through the side frame 162 and not only carries the gear 140 but on its extreme outer end it carries a gear 166. This gear is an elliptic gear mounted eccentrically on the shaft, see particularly Fig. 5. A similar gear 168 is mounted on the drive shaft

166 eccentrically thereto. The eccentrically mounted gears 166 and 168 are always in mesh with each other.

The shaft 170 for the lower rotor 132 of the web-shaping mechanism projects through the side frame 162 and not only carries the gear 144 but on its outer end it carries gear 172. This elliptic gear is mounted eccentrically on the shaft, see Fig. 5. A similar gear 174 is mounted on the drive shaft 158 eccentrically thereto. The eccentrically mounted gears 172 and 174 are always in mesh with each other.

Inasmuch as the gears 166 and 168 and gears 172 and 174 are mounted eccentrically on their respective shafts, it will be appreciated that while the motor 146 will drive these gears and the web-shaping and web-severing rotors at a constant number of revolutions per minute, the linear speed of the web-severing rotors and web-shaping rotors will not be constant throughout each revolution of the rotors.

Accordingly, for a given length of bag, the gears 166, 168 and 172, 174 are so set that at the instant the web-shaping rotors engage the web to shape the leading end of the web, these rotors will be travelling at a desired cutting speed relative to web speed. Likewise when the web-severing rotors engage the web these rotors will be traveling at a desired cutting speed relative to web speed.

When changing to another length of bag, the web is either speeded up or slowed down, depending upon whether a longer or shorter bag length is desired. Under these circumstances the eccentrically mounted gears 166, 168 and 172, 174 are reset by rotating them on their respective shafts to alter the relation between these gears and their respective web-severing rotors and web-shaping rotors, and hence alter the peripheral speed of these rotors at the instant the rotors of each pair are rotated into cooperative relation, so that at that instant, the rotors will be traveling at the proper peripheral cutting speed relative to the new web speed.

From all of the foregoing, it will be seen that we have provided a web handling machine wherein the leading end of the web is always shaped in advance of cutting or severing the web for a bag length. It will be apparent also that very simple mechanism has been provided for adjusting the web-shaping mechanism and the web-severing mechanism in accordance with variations in web speed when changing bag lengths with the assurance that each of these mechanisms will engage the web at proper cutting speed ratio to web speed so that tearing of the web or plugging of the machine are avoided.

It is to be understood that changes may be made in the details of construction and arrangement of parts herein described and illustrated within the purview of my invention.

What we claim is:

1. Web cutting mechanism comprising in combination a pair of rotary cutting elements adapted to receive the leading end of a continuously advancing web between them and to impart a predetermined shape to the web end, a second pair of rotary cutting elements to the rear of the first pair and adapted to receive the continuously advancing web between them and arranged completely to sever the web to the rear of the shaped leading end after the completion of the shaping of the leading end, means for rotating said cutting elements at a fixed number of revolutions per minute, rotatable means for

effecting continuous advance of the web through said cutting devices, means for varying the linear speed of the web without varying the peripheral speed of the cutting elements and means for varying the peripheral speed of the cutting elements without varying the revolutions per minute of said cutting elements, whereby the severed sections of the web may be varied in length, the cutting elements when contacting the web travelling at a predetermined peripheral speed relationship to the linear speed of the web.

2. Web-cutting mechanism comprising in combination a pair of rotary cutting elements geared to each other and adapted to receive the leading end of a continuously advancing web between them and to impart a predetermined shape to the web end, a second pair of rotary cutting elements to the rear of the first pair and adapted to receive the continuously advancing web between them and arranged completely to sever the web to the rear of the leading end after the leading end has been completely shaped, gearing arranged to drive each pair of cutting elements at a fixed number of revolutions per minute but at non-uniform peripheral speed, and means for varying the setting of said gearing to vary the peripheral speed at which the cutting elements are moving when brought into engagement with the traveling web whereby the cutting elements will be moving at a predetermined peripheral speed relationship to web speed under all conditions of web speed at the instant of operation of the cutting elements.

3. Web-cutting mechanism comprising in combination a pair of feed rollers for continuously advancing a web, means for varying the speed of said rollers thereby to vary the linear speed of the web, a pair of rotatable cutting elements geared together, and adapted to receive the leading end of the web between them, said elements when rotated into cooperative relation to each other shaping the leading end of the web to a predetermined shape, a second pair of rotatable cutting elements intermediate the first mentioned cutting elements and the feed rollers, the last mentioned cutting elements being geared together and adapted when rotated into cooperative relation completely to sever the web to the rear of its leading end after the leading end has been completely shaped, gear trains for the cutting elements for rotating the same at a constant number of revolutions per minute, and means for adjusting said gear trains so as to vary the peripheral speed of the cutting elements as they are brought into cooperative relation to conform to variations in the linear speed of the web without altering the revolutions per minute of the cutting elements.

4. Web cutting mechanism comprising in combination a pair of feed rollers for continuously advancing a web, change speed gearing for varying the linear speed of the web, a pair of rotatable cutting elements geared together, in the path of the advancing web, and adapted when rotated into cooperative relation to impart a predetermined shape to the leading end of the web, a second pair of rotatable cutting elements intermediate the first pair of said feed rollers, said last mentioned cutting elements being geared together and adapted when rotated into cooperative relation completely to sever the web to the rear of its leading end after the leading end has been completely shaped, gear trains for the cutting elements, each comprising a gear rotated at a fixed number of revolutions per

minute and connected to one of the gears of the cutting elements through an adjustable crank arm and crank pin, whereby the peripheral speed of the cutting elements when brought into co-operative relation may be varied, without altering the revolutions per minute of the cutting elements, to accommodate the mechanism to variations in the linear speed of the web.

5. Web-cutting mechanism comprising, in combination, rotatable, intermittently operating web-shaping mechanism adapted to receive the leading end of a continuously advancing web and impart a predetermined shape to the web end, a rotatable, intermittently operating web-severing mechanism to the rear of the web-shaping mechanism adapted completely to sever the web to the rear of the leading end after the completion of the shaping of the leading end, means for rotating said web-shaping mechanism and said web-severing mechanism at a fixed number of revolutions per minute, rotatable means for effecting continuous advance of the web, means for varying the linear speed of the web without varying the peripheral speed of the web-shaping and web-severing mechanisms, and means for varying the peripheral speed of the web-shaping and web-severing mechanisms without varying their revolutions per minute, whereby the severed web sections may be varied in length, the web-shaping and web-severing mechanisms, when contacting the web, traveling at a predetermined peripheral speed relationship to the linear speed of the web.

6. Web-cutting mechanism comprising, in combination, rotatable means for continuously advancing the web, rotatable, intermittently operating shaping mechanism for shaping the leading end of the continuously advancing web, rotatable web-severing mechanism intermediate the web-advancing means and the web-shaping mechanism arranged completely to sever the web to the rear of the leading end after the completion of the shaping of the leading end, means for varying the speed of rotation of the web-advancing means to vary the linear speed of the web without varying the peripheral speed of the web-shaping and web-severing mechanisms, means for varying the peripheral speed of the web-shaping and web-severing mechanisms without varying their revolutions per minute, whereby the length of the severed sections may be varied, the web-shaping and web-severing mechanisms traveling at a predetermined peripheral speed relationship to the linear speed of the web when contacting the web.

7. Web-cutting mechanism comprising, in combination, web-advancing means for continuously advancing the web, intermittently operating web-shaping mechanism for shaping the leading end of the web, intermittently operating mechanism intermediate the web-advancing means and the web-shaping mechanism for completely severing the web to the rear of its leading end, means for varying the linear speed of the web without varying the peripheral speed of the web-shaping and web-severing mechanisms, means for varying the peripheral speed of the web-shaping and web-severing mechanisms to vary the length of the severed sections, the web-shaping and web-severing mechanisms moving at a predetermined speed relationship to the linear speed of the web when contacting the web.
- 10 8. Web-cutting mechanism comprising, in combination, a pair of rotary cutting elements geared to each other and adapted to receive the leading end of a continuously advancing web between them and to impart a predetermined shape to the web end, a second pair of rotary cutting elements to the rear of the first pair and adapted to receive the continuously advancing web between them and arranged completely to sever the web to the rear of the leading end after the leading end has been completely shaped, an elliptic gear on the shaft of one of the rotors of each pair of rotary elements, a drive shaft for each pair of cutting elements, said shafts being geared to each other by an intermediate gear, an elliptic gear on each of said drive shafts in mesh with the first-mentioned elliptic gears, and means for varying the setting of the elliptic gears on their shafts.
